US00D873084S

(12) **United States Design Patent** (10) **Patent No.:** **US D873,084 S**
(45) **Date of Patent:** **** Jan. 21, 2020**

(54) **REUSABLE SEALABLE SANDWICH BAG**

- (71) Applicant: **ZIP TOP, LLC**, Austin, TX (US)
(72) Inventors: **Rebecca M. Finell**, Austin, TX (US);
Joshua J. Nelson, Mesa, AZ (US)
(73) Assignee: **ZIP TOP, LLC**, Austin, TX (US)
(**) Term: **15 Years**
(21) Appl. No.: **29/699,301**
(22) Filed: **Jul. 24, 2019**

Related U.S. Application Data

- (63) Continuation-in-part of application No. 29/618,099, filed on Sep. 19, 2017.
(51) **LOC (12) Cl.** **07-07**
(52) **U.S. Cl.** **D7/602**
(58) **Field of Classification Search**
USPC D7/601, 602; D9/430; 426/85
CPC A47G 19/02; A47G 19/025

(57) **CLAIM**

The ornamental design for a reusable sealable sandwich bag, as shown and described.

DESCRIPTION

FIG. 1 illustrates a perspective top/front view of a reusable sealable sandwich bag, showing the new, original and ornamental design, wherein the sandwich bag is open and unsealed.

FIG. 2 shows a front view of the reusable sealable sandwich bag shown in FIG. 1.

FIG. 3 shows a back view of the reusable sealable sandwich bag shown in FIGS. 1-2.

FIG. 4 shows a left side view of the reusable sealable sandwich bag shown in FIGS. 1-3.

FIG. 5 illustrates a right side view of the reusable sealable sandwich bag shown in FIGS. 1-4.

FIG. 6 shows a top view of the reusable sealable sandwich bag shown in FIGS. 1-5; and,

FIG. 7 shows a bottom view of the reusable sealable sandwich bag shown in FIGS. 1-6.

1 Claim, 4 Drawing Sheets
